Patented July 22, 1919.

UNITED STATES PATENT OFFICE.

THOMAS B. RIDER, OF LOS ANGELES, CALIFORNIA, ASSIGNOR OF ONE-HALF TO
ADOLPHE DANZIGER, OF LOS ANGELES, CALIFORNIA.

X-RAY TUBE.

1,310,714.

Specification of Letters Patent. Patented July 22, 1919.

Application filed January 18, 1918. Serial No. 212,529.

To all whom it may concern:

Be it known that I, THOMAS B. RIDER, a citizen of the United States, residing at Los Angeles, in the county of Los Angeles and 5 State of California, have invented a new and useful X-Ray Tube, of which the following is a specification.

This invention relates to X-ray tubes in which the electrons travel at high velocity 10 between the cathode and the target formed by the anode.

One object of the invention is to prevent overheating and melting of the metal on the surface of the target or anode by providing 15 means for changing the focal spot, when the tube is being used with short interruptions for a number of operations.

Another object is to lengthen the life of 20 such targets or anodes by providing separate independent focal spots in the surface of the anode so that a deforming of the surface of one spot cannot influence any of the other spots.

Another object is to provide means of 25 holding the cathode and anode in suitable relation so that a stream of cathode rays can impinge on the surface of the anode.

Other objects will appear from the accompanying drawing as well as from the 30 following description and appended claims.

In the drawing—

Figure 1 is a fragmentary longitudinal sectional view of the adjusting means for 35 changing the relation between the cathode and the anode.

Fig. 2 is a fragmentary side elevation of the anode showing the outline of inserted material in the surface of the anode.

Fig. 3 is the front elevation of the anode, 40 several separate insets in the surface of the anode being illustrated in the manner I prefer.

Fig. 4 is a front elevation of a rotating target for the anode.

Fig. 5 is a fragmentary longitudinal section 45 through the anode slightly modified with the rotating target in position.

Similar numbers refer to similar parts throughout the several views.

In Fig. 1, 4 designates the X-ray tube and 50 5 the extension tube, which are usually made of glass. The stem 6 is fused into the end 7 of the tube 6 projecting practically concentrically into the X-ray tube. The cathode 8 is slidingly and turnably mounted on the 55 stem 7 being provided with an extension 9, forming the housing for the operating mech-

anism. The cathode with extension being preferably made of aluminum, which can naturally not be influenced by a magnet, I prefer material which can be influenced by a magnet for the operating parts for which a recess 10 is provided in the extension of the cathode. Lugs 11 are provided at a suitable place for the blocks 12 and 13. These blocks are preferably made of steel or other suitable material which can be influenced by a magnet, and being pivotally connected with the lugs, the blocks can naturally be drawn toward the wall of the glass tube 5 by holding a magnet on the outside of the glass tube. The rings 14 and 15 pivotally connected with each other at 16 are disposed on the stem 6 having holes 17 of a size slightly larger than the diameter of the stem so that, when in the position shown, the edges of the material near the holes set or clamp themselves tightly to the stem 6 while in a compressed position, illustrated in dotted lines at 18, the holes being naturally large enough to easily slip over the stem to any desired position. Bosses 19 are provided on the rings 14 and 15 at suitable places forming the support for the spring 20.

Holding a magnet to the outside of the extension tube 6 near the blocks 12 and 13, naturally causes a drawing of the blocks, with their free ends 21 sliding along the outer flat surfaces of the rings, toward the edges 22 to the position indicated in dotted lines at 23, bringing the rings to the compressed position indicated in dotted lines at 18, in which position the rings can freely be moved, slipping over the stem as described above, to be set on the stem in any desired position by removing the magnet. 95

In this collapsed position of the rings in which they naturally do not clamp the cathode to the stem 6, the whole cathode with the extension 9 and with the embodied operating means (rings 14 and 15, and blocks 12 and 13 with the spring 20) can be moved longitudinally on the stem or around the stem by the same magnet which caused the collapsing of the operating means, by keeping the blocks 12 and 13 influenced and moving the magnet in the desired direction. 100

The anode 24, which is in its normal position opposite the cathode 8 within the X-ray tube, is, in its surface, provided with a suitable number of suitable recesses for the insets 25. The insets are preferably made of highly refractory metal. 11

To allow and assure a focusing of the cathode to the center of each of the several insets, the stem 6 is made with a corresponding number of flat surfaces, having four insets in the surface of the anode naturally calls for a square bar for the stem 6 and eight insets naturally make an eight-cornered bar for the stem 6 necessary, as will easily be understood. An eight-cornered bar 10 is illustrated in the drawing in Fig. 1. The holes in the rings 14 and 15 naturally need not to be of a shape corresponding to the stem, the setting or clamping of the operating means to the stem will be possible as long as the upper and lower edges in the holes engage with the stem which will be the case with square or oval holes as long as two flat sides are provided in the holes. After having the rings contracted or compressed as described above and set the cathode to a position desired, the magnet is removed from near the extension tube 5 causing the releasing of the blocks thereby allowing the spring to press the rings back 20 to the engaging position illustrated in Fig. 1. It will easily be understood that such releasing can be effected to focus the cathode to any of the insets in the surface of the anode, and, if not quite to the center of the insets, the suitably shaped holes 17 will settle on the correspondingly shaped stem 6 to bring the focus from the cathode to the center of one of the insets.

In the slightly modified construction of the anode illustrated in Figs. 4 and 5, the inserts 25 are embodied in an extra plate 26, which is rotatably mounted on the front of the anode 24, the boss 27 being provided on the target-plate 27 turnably fitting in a suitable hole or recess in the anode. This target-plate 26 is also provided with balancing ball or weight extensions 28 for changing the position of the target-plate by the gravity of the weight on the target-plate. Since it 35 is desirable to change the position of the target-plate 26 always a certain distance, that is from one inset to another to bring the focus of the cathode to one of the insets, a tumbler or locking pin 29 is slidably embodied in the anode being pressed by the spring 30 into one of the notches or recesses 31 in the target-plate 26. Such notches or recesses 31 are naturally arranged corresponding to the insets 25 to assure a proper 45 position for the insets in relation to the focus from the cathode, as will easily be understood.

If desired to change the focus from the cathode to a new, or from one inset to another inset, the whole X-ray tube is shaken

enough to cause the weight extension 28 to turn the target-plate; care is taken, while shaking the X-ray tube in such a manner that the target-plate turns to bring the desired inset to the desired position.

This modification is provided to enable a person to change the focus spot when not having a suitable magnet on hand for such an operation as is required when changing the focus by turning the cathode in the manner described in relation to Fig. 1.

As illustrated in Fig. 1, the focusing face of the cathode naturally must be arranged eccentrically to the bore in the cathode, or the center of the focusing face eccentrically 75 to the center of the supporting stem 6, so as to bring the focus to the different insets when turning the cathode on the stem as described above.

Having thus described my invention, I claim:

1. In an X-ray tube an anode having a suitable number of independent insets, and a cathode having means for focusing the cathode toward any of the insets in the 85 anode.

2. In an X-ray tube, a cathode comprising a body having a concentric bore and having a focusing face transverse to the bore with the center of the focusing face 90 eccentric to the center of the bore in the body, a stem in the tube forming a support for the cathode, the cathode being turnably and slidably disposed on the stem, and clamping members engaging with the body 95 of the cathode having means to engage with the stem for holding the cathode in focusing position, the clamping members also adapted for moving the cathode on the stem.

3. In an X-ray tube an anode having a 100 suitable number of insets, a cathode having means for focusing the same toward any of the insets in the anode, and a stem forming the support for the cathode having a number of flat surfaces longitudinally to the 105 stem corresponding to the number of the insets in the anode.

4. In an X-ray tube an anode having a suitable number of insets of suitable material to withstand the stream of cathode rays 110 consisting of electrons traveling at high velocity and having also means for changing the focus of the cathode to any of the insets in the anode.

In testimony whereof I hereunto affix my 115 signature in the presence of two witnesses.

THOMAS B. RIDER.
